(57) **CLAIM**

The ornamental design for a hydraulic multi-coupler having an optional port, as shown and described.

DESCRIPTION

FIG. 1 is a first perspective environmental view of a hydraulic multi-coupler having an optional port of the present design attached to a five-port connector of a header shown in dashed lines.

FIG. 2 is a second perspective environmental view of the hydraulic multi-coupler having an optional port of FIG. 1 attached to a seven-port connector of a header shown in dashed lines.

FIG. 3 is a front view of the hydraulic multi-coupler having an optional port of FIG. 1.

FIG. 4 is a rear view of the hydraulic multi-coupler having an optional port of FIG. 1.

FIG. 5 is a left side view of the hydraulic multi-coupler having an optional port of FIG. 1.

FIG. 6 is a right side view of the hydraulic multi-coupler having an optional port of FIG. 1.

FIG. 7 is a top side view of the hydraulic multi-coupler having an optional port of FIG. 1; and,

FIG. 8 is a bottom side view of the hydraulic multi-coupler having an optional port of FIG. 1.

The broken line showing of the article support and handle in FIGS. 1 and 2 illustrates the environment of the claimed design and forms no part thereof. The remaining broken lines in the drawings illustrate portions of the hydraulic multi-coupler having an interference tab and form no part of the claimed design.

1 Claim, 8 Drawing Sheets
